UNITED STATES PATENT OFFICE.

ALBERT PICK, OF CHICAGO, ILLINOIS.

DESIGN FOR A DRINKING VESSEL.

No. 37,546.

Specification for Design.

Patented Sept. 12, 1905.

Application filed December 23, 1904. Serial No. 238,152. Term of patent 7 years.

To all whom it may concern:

Be it known that I, ALBERT PICK, a citizen of the United States, residing at Chicago, in the county of Cook and State of Illinois, have invented a new, original, and ornamental Design for a Drinking Vessel.

The accompanying illustrates a design in accordance with my invention.

I claim as my invention—
The ornamental design for a drinking vessel as shown.

ALBERT PICK.
